UNITED STATES PATENT OFFICE.

JOHN H. IRWIN, OF MORTON, PENNSYLVANIA.

LAMP-STOVE.

SPECIFICATION forming part of Letters Patent No. 230,636, dated August 3, 1880.

Application filed April 16, 1880. (No model.)

To all whom it may concern:

Be it known that I, JOHN H. IRWIN, of Morton, in the county of Delaware and State of Pennsylvania, have invented certain new and 5 useful Improvements in Lamp-Stoves, of which the following is a full, clear, and exact description, reference being had to the accompanying drawings and to the letters of reference marked thereon, the same not having been to my 10 knowledge heretofore patented in any foreign country.

My invention has relation to that class of stoves wherein the air for the support of combustion is delivered to the under side of the 15 burner-plate through channels or conduits fed from the exterior air, the incoming air and outgoing products of combustion (one or both) being controlled in direction by deflecting-surfaces in such manner as that any disturbances 20 in the surrounding atmosphere shall always insure an accelerated outflow of the products of combustion, or an accelerated inflow of fresh air to feed the flame, or both together, as heretofore fully explained by me in previous applications for Letters Patent on stoves, the dates 25 of filing of which will be given hereinafter.

The principal object of my present invention is to provide increased security in the matter of insuring an injection of fresh air to 30 feed the flames; and a further object is to provide such an arrangement of parts as will tend toward simplicity of construction, ease of management and care, increased heating-surface, and facility of packing for transportation, &c.

To accomplish these objects the invention 35 involves the employment of a secondary air-feeding conduit leading to the under side of the slotted burner-plate and adapted to supply a volume of fresh air independently of the principal or primary conduit, a hinged burner-plate, and other details or peculiarities of construction and arrangements of parts, all of which will be hereinafter first fully described, and then pointed out in the claims.

In the drawings, Figure 1 is a sectional view 45 of a stove constructed and arranged to operate in accordance with my improvements, showing an independent air-feeding conduit, the removable or detachable chimney, and other details of construction. Fig. 2 is a similar view 50 of a stove, showing the application of the re-

movable or adjustable chimney to a stove without the second or independent air-feeding conduit; and Fig. 3 is a sectional view of the stove shown in Fig. 2, taken upon a plane through 55 the axis of the wick-tubes and at right angles to that of Fig. 1.

Like letters of reference, wherever they occur, indicate corresponding parts in all the figures.

A is the oil-pot, and B B the wick-tubes, secured therein in any preferred way. C is the 60 pot-hole plate, made removable, and intended for the support of the cooking-utensils.

D is the main air-feeding conduit, communicating with the under side of the burner-plate and supplying fresh air for the support of combustion, the conduit being provided at the entrance with deflecting plates, which so direct impinging currents as to cause them either to 65 enter the conduit or to induce an accelerated outflow from the discharge end of the circuit, either of which results will secure an increased upward flow of air through the slotted burner-plate, and thus increase, rather than retard, 70 combustion, as I have already fully explained in applications for patents the dates of which are mentioned hereinafter.

In the drawings, Fig. 1, a broken circuit is shown, and at the point of rupture I place a 80 combined injector and ejector composed of the deflecting-plates a b c d e, and in all respects substantially like what is now known as the "perfect" injector and ejector—such, for instance, as shown in my patent of May 19, 1874, 85 No. 150,958, though for the purposes of this part of the invention any device located at this point which will cause an injection on the side of the conduit leading to the burner-plate or an ejection from the other side, or both together, will answer the purposes.

While the injector and ejector at the mouth of the conduit will, under ordinary circumstances, maintain the flame in a steady condition, it is apparent that a current below this 95 mouth might be moving without sensibly affecting any air with respect thereto; and therefore I locate the second combined injecting and ejecting device at a point in the conduit where it may be impinged upon by all currents 100 likely to strike the stove below the end or main entrance of the conduit, and from this

arrangement it will be seen that the sensitiveness of the structure to the beneficial influence of air-currents will be greatly augmented, each current being made to increase the combustion, and none capable of retarding it.

5 The flame may be said to be located within a circuit of air-currents controlled in direction and made to follow one course—viz, from the mouth of the feed-air conduits through 10 the conduit upwardly through the burner-plate, under the top plate, or under or through whatever character of vessel or utensil may be placed thereon, and then escaping at a point in close proximity to the inlet of the conduit. 15 The illustration of the ruptured conduit will serve to show that the circuit above-named may be broken at any point, provided there be devices arranged in connection with the break which will mechanically compel an increased flow of air through it in the proper direction to support combustion. As many of these breaks as desired may be made in the circuit, provided that at each one the proper deflecting-surfaces be arranged. Whether the circuit 20 be completed, as in Fig. 2, or broken, as in Fig. 1, or arranged in any one of a multitude of ways, I find it desirable and advantageous to employ, in addition to the primary air-feeding conduit, a second conduit, adapted 25 to deliver air to the under side of the burner-plate and operating independently of the primary or principal conduit.

30 One form of such a secondary independent conduit is indicated in Fig. 1, which will serve as an illustration of the principles of this part of the invention.

35 The main feeding-tube D discharges into a channel or chamber, E, communicating with the under side of the slotted burner-plate represented at F.

40 Surrounding chamber E is a conduit, G, also discharging beneath F, and having no communication with E, the contents of the two conduits being discharged at about the same level beneath the burner-plate. The open end of G is provided with injector-surfaces—such, for instance, as at f g h—so that air-currents impinging thereon shall be injected.

45 The air injected through G will augment the supply of feed-air, and since the burner-slot is of large area compared with the discharge-opening of chamber E, the tendency of the injected air will always be upwardly through the burner-slot, or in the proper direction for the support of combustion.

50 The independent air-feeding current may be increased in volume by exterior disturbances which do not affect the main supply, and, conversely, the increased supply might be augmented independently of the secondary current, the two together, however, producing an extremely sensitive and efficacious arrangement.

55 The secondary conduit may be variously constructed and arranged. Instead of carrying its contents beneath D and E, it might be made to deliver them at a point above the outlet of

E, and instead of being made to surround E, one or more tubes might be carried therethrough and made to deliver their contents at any preferred point.

60 Instead of being made to surround the chimney or made annular in form, any form might be adopted, it being only necessary that the effects of ejection are guarded against, and that the main and subordinate currents are independent of each other. This principle may be applied upon any form of stove wherein the direction of the currents are under control, and it may be stated that the same principle of 65 operation is advantageously applicable to various illuminating devices wherein the currents are controlled or counterbalanced, as in many forms of lamps and lanterns patented to me, particularly of the class shown in my patents 70 of May 28, 1867, January 7, 1868, and June 14, 1870, the application of the principle thereto requiring some changes as to form and location or arrangements of parts, all of which will be embodied in future applications for patents. 75

80 The oil-pot A is made to extend beneath the superstructure of the stove, and forms the base thereof, being supported upon suitable feet or legs a a, as plainly shown. Upon the top of the oil-pot are suitable lugs l, which are made 85 to support the upper parts of the structure at a little distance above the top of the oil-pot, either directly, as in Fig. 1, or through the medium of corresponding projections p, as in Figs. 2 and 3.

90 H is the chimney, made to extend down to the burner-plate F, and forming the flame-chamber.

95 The assembling-bolts K unite the plate I with base-plate J, and serve to maintain these parts in their proper relative positions.

100 The top plate, C, is made removable from the stove-body, and may be secured in place by any of the known means.

105 Between plates I and C there is ample room for the adjustment of chimney H, which, for all ordinary purposes of lighting and cleaning the burners, may simply be lifted up from over the burner-plate, being guided by the walls of the aperture in plate I, and it finds its support 110 thereon when down in its place.

115 To hold the chimney H in its elevated position, slightly above the burner-plate, I attach to the chimney a hinged brace, L, (shown in dotted lines, Fig. 1,) which brace may be turned down when the chimney is elevated, and made to rest upon any convenient part of the lower portion of the stove, thus maintaining the chimney in its elevated position. When not in use brace L is closely folded against the 120 wall of the chimney and out of the way.

125 The whole upper part of the structure may be hinged to the oil-pot, as at m n, Fig. 1, and the upper part thrown back upon this hinge whenever desired.

130 On the exterior of the top flue, O, I hinge a brace, L', (shown in dotted lines,) the same being of sufficient length to rest upon the top of the oil-pot, and, when the upper parts of the

stove are tipped back, serves as a support therefor, maintaining them in the required position. When not in use brace L' finds a convenient lodgment against the wall of flue O.

5 The burner-plate F is preferably hinged, as plainly shown at r, Fig. 2, so that it may be readily thrown back from over the wick-tubes whenever required, and be as conveniently replaced, without the usual necessary adjustments.

The upper part of the stove is enlarged, as at T T, beyond the walls of the chimney, affording an enlarged expansion-chamber for the combined air and gases, in which enlargement 15 the products of combustion, &c., find lodgment, imparting their heat effectually to an enlarged radiating-surface; and this construction enables me to considerably increase the size of the pot-hole plate, or the number of pot-holes therein, without detracting from the heat-giving qualities of the stove. With this enlargement any number of wick-tubes may be employed, and the greater the number of tubes the greater may be the enlargement, carrying 25 the stove out to any desired dimensions.

In either form of stove represented it will be observed that the fresh-air conduit is supported from the rear of the oil-pot by suitable standards prepared for the purpose.

30 The inclined conduit shown in Fig. 2 may be broken and provided with injecting and ejecting surfaces, same as in Fig. 1, and the burner-plate in Fig. 1 may be hinged, same as in Fig. 2.

The secondary and independent air-conduit 35 G, or its equivalent, may be adopted, in connection with the arrangement shown at the base of the stove in Fig. 2, as well as in any other stove of the same general type.

The slotted burner-plate may be in the ordinary form of cone-plate, or it may be flat and simply perforated for the passage of the flame, as indicated in Fig. 3, or provided with downwardly-inclined surfaces, as in Fig. 2, all of which forms are well known to be old.

40 The continuous air and gas circuit within which the flame is located, and some of the peculiarities of construction indicated in Fig. 2, are made subjects of claims in prior applications for patents filed August 8, 1879, and February 14, 1880, (the former patented April 13, 1880,) and therefore it is not intended to make 50 any claims to such features herein, except in the relative combinations or arrangements hereinafter specified.

55 Having now fully described my invention, I will add that in practice the features constituting the improvements are found to admirably answer the several purposes and objects of the invention, as previously stated.

60 What I claim as new herein, and desire to secure by Letters Patent, is—

1. In a stove of the character herein specified, wherein the burners are located within a circuit having main outlet and inlet openings in

close proximity to each other, the fresh-air 65 conduit, broken between the inlet and burners and provided with air-deflecting surfaces at the point of rupture, substantially as and for the purposes set forth.

2. The combination, with an air-conduit 70 adapted to supply fresh air to the under side of the burner-plate, and in which the direction of the feed-air is controlled by means of air-deflecting surfaces operating in conjunction with said conduit, of a second conduit, independent of the first named, adapted to supply an independent volume of air to the under side of the burner-cone to assist in feeding the flame, substantially as and for the purposes set forth. 75

3. In combination with the burner-plate, a chimney discharging into a flue beneath the top or pot-hole plate, said chimney being made adjustable in the opening in the bottom of said flue and provided with a hinged brace for maintaining it in its elevated position, substantially 80 as shown and described. 85

4. The combination, as before set forth, of air-duct D, chimney H, and heating-flue O, forming together an air and gas circuit of the 90 character described, within which the burners are located, the oil-pot extending beneath the superstructure, and air-duct D being supported thereon, substantially as shown and described. 95

5. The combination of air-duct D, having an injector at its mouth and secondary ejecting and injecting surfaces between its extremities, burner-plate F, chimney H, and heating-flue O, discharging at a point over the air-inlet 100 and provided with an ejector at its outlet, substantially as shown and described.

6. The combination of air-duct D, having an injector at its mouth and ejecting and injecting surfaces between its extremities, burner-plate F, independent air-flue G, chimney H, and heating-flue O, discharging at a point over the air-inlet, and provided with an ejector at its outlet, substantially as shown and described. 105 110

7. The combination of the oil-pot, the upper parts of the stove hinged thereon, as at m n, and movable, as explained, and the brace L', hinged to the wall of the heating-flue opposite the hinge beneath the top plate of the stove, 115 and serving to maintain the swinging parts in their elevated position, the bottom of the brace resting upon the lower portion of the stove, substantially as and for the purposes set forth. 120

In testimony that I claim the foregoing I have hereunto set my hand in the presence of two witnesses.

J. H. IRWIN.

Witnesses:

WORTH OSGOOD,
ARTHUR M. PIERCE.
